Dennis S. Schell(57) **CLAIM**

The ornamental design for a high bay LED light fixture, substantially as shown and described.

DESCRIPTION

FIG. 1 is a bottom perspective view of an embodiment of the new design;

FIG. 2 is a top perspective view of the embodiment;

FIG. 3 is a top view of the embodiment;

FIG. 4 is a bottom view of the embodiment;

FIG. 5 is a right side view of the embodiment;

FIG. 6 is a front view of the embodiment; and,

FIG. 7 is a left side view of the embodiment.

The design consists of the features of shape, ornament and configuration of the article shown in the drawings. The broken lines shown in the drawings are for the purposes of illustrating portions of the article that form no part of the claimed design. The rear view is a mirror image of the front view and is therefore omitted.
